HOOD FOR TANKS AND THE LIKE

Albert H. Fine, Oak Park, Ill.

Application February 23, 1949, Serial No. 77,820

5 Claims. (Cl. 220—85)

1

This invention relates to control equipment for bottled gas installations, and particularly to enclosing housings, or hoods for the gas supply fittings that are used in such bottled gas installations.

Where bottled gas is used as a fuel in domestic or other places, it is customary to provide two tanks of fuel gas so that one such tank may be connected as a fuel supply source while the other tank is held in reserve and is connected to the supply line when the gas in the original container is exhausted.

The tanks that are thus provided are ordinarily mounted outside of the building in which the gas is to be consumed, and to connect the tanks to the connections that extend from the house, it is necessary to provide connecting fittings and valves for association with the two tanks of gas, together with suitable check valves and pressure reducing valves so that the high pressure gas from the containers may be fed to the house line at a uniform reduced pressure. In order that the valve fittings that are thus required may be properly housed and protected, it is customary to afford an enclosing hood that may be locked in an enclosing relation by the workman after the tanks of gas have been put in place and properly connected to such supply fittings.

Heretofore it has been customary to support such hoods on a special stand which is so constructed that the hood is supported at a height that is determined by the size of the tanks that are to be associated therewith, such stands often affording a base upon which the tanks may be rested. Such stands have been found to be relatively expensive, and it is an important object of the present invention to simplify and reduce the cost of the hood structure for use in connection with bottled gas installations of the aforesaid character. More specifically, it is an object of the present invention to enable such hoods to be supported in a novel and expeditious manner without the necessity for provision of a stand in association therewith; and a related object is to enable the bottles to act as the supporting structure for the hood, in a novel and expeditious manner, to thereby simplify the structure and reduce the cost of such protective hoods.

Another object is to afford a novel hood structure of the aforesaid character which will properly enclose the connecting fittings and which may be supported in a novel manner by one such gas container while the other gas container is being removed and replaced.

2

A further object of my invention is to afford a hood which is effective to hold such gas containers in operative relation to each other in a novel and expeditious manner.

Yet another object is to provide a hood which may be firmly secured to such gas containers in a novel and expeditious manner and may be quickly and easily released therefrom.

Other and further objects of the present invention will be apparent from the following description and claims and are illustrated in the accompanying drawings which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a front elevational view of a hood structure embodying the features of the invention;

Fig. 2 is a vertical longitudinal sectional view of the structure shown in Fig. 1;

Fig. 3 is an enlarged detail view of a portion of the device shown in Fig. 2, showing the parts in a different relationship;

Fig. 4 is a top plan view of the hood structure;

Fig. 5 is a top plan view of the mounting plate that forms the bottom wall of the enclosing hood;

Fig. 6 is a transverse sectional view taken substantially along the lines 6—6 in Fig. 4; and

Fig. 7 is an enlarged end elevational view of a portion of one end of the hood.

The housing or hood 20 shown in the accompanying drawings to illustrate a preferred embodiment of my invention, comprises, in general, a base plate 22 adapted to be simultaneously mounted on two commercial gas containers such as, for example, bottles B1 and B2, and a cover member 24 adapted to be removably and hingedly mounted on the base plate 22 to afford a protective covering or guard for the upper end portion of such bottles and the valves and other fittings normally mounted thereon when such bottles are in use.

As is best seen in Figs. 1, 2 and 5, the base plate 22 is of substantially flat elongated formation and has two elongated, and transversely extending recesses 26 and 27 formed in the opposite end portions thereof, respectively, Fig. 5, the slots 26 and 27 extending inwardly from one lateral edge

28 of the plate 22 and terminating in spaced relation to the other lateral edge 29, thereof. Two groups of six bosses 30 and 31 project downwardly from the lower face of the base plate 22, Figs. 1 and 5, with each of the groups of bosses 30 and 31 being arranged in spaced relation around the recesses 26 and 27, respectively, and affording supporting members adapted to support the base plate 22 on the upper end portion of gas cylinders, as will be discussed in greater detail hereinafter. Suitable reinforcing ribs 32 and 33 project downwardly from the lower face of the base plate 22 to strengthen the central portion of the plate.

Two substantially L-shaped ears or lugs 36 and 37 having two legs 36a and 36b, 37a and 37b, respectively, project outwardly from the end of the base plate 22 in which the recess 26 is formed, Figs. 2 and 5, the legs 36a and 37a forming substantially straight-line extensions of the base plate 22, and the legs 36b and 37b being disposed on the outer ends of the legs 36a and 37a, respectively, and projecting substantially perpendicularly upwardly therefrom, Figs. 2 and 3. Two ears 40 and 41, similar to the ears 36 and 37, and each having two legs 40a and 40b, 41a and 41b, respectively, project outwardly from the other end of the plate 22 substantially in alignment with the ears 36 and 37, respectively. As is best seen in Fig. 5, two slots 43 and 44 are formed in the base plate 22 between the ears 36 and 37, and the ears 40 and 41, respectively, and two ears 46 and 47 project upwardly from the upper surface of the base plate 22 adjacent to the inner edge portion of the slots 43 and 44, respectively. The ears 46 and 47 each comprises a base leg 46a and 47a, respectively, projecting upwardly at an acute angle from the base plate 22, and an upper leg 46b and 47b, respectively, projecting horizontally outwardly from the upper end portion of the legs 46a and 47a, respectively, the ears 46 and 47 being so disposed on the base plate 22 that the legs 46a and 46b, and 47a and 47b, extend outwardly over the slots 43 and 44, respectively.

The cover member 24 is substantially dish-shaped and may be made of any suitable material such as, for example, cast aluminum, and comprises a top wall 50, and walls 52 and 53 and side walls 55 and 56, Figs. 2 and 6, and has an open bottom. Two recesses or slots 48 and 49, Fig. 1, are formed in the central lower edge portion of the side walls 55 and 56, respectively, and afford openings through which feed lines may project outwardly from the hood 20 when the latter is in use, as will be discussed in greater detail presently.

Two spaced slots or recesses 58, Fig. 7, are formed in the lower edge portion of each of the end walls 52 and 53, and afford the lateral boundaries for tongues 57 and 59 disposed in the central edge portions of the end walls 52 and 53, respectively, Figs. 2, 3 and 7. The slots 58 are complementary in size to the ears 36, 37, 40 and 41, and are so arranged in the end walls 52 and 53 of the cover member 24 that when the cover member 24 is mounted on the base plate 22, in normal position, the legs 36a, 37a, 40a and 41a of the ears 36, 37, 38 and 39 each projects outwardly through a corresponding one of the slots 58.

Ears or lugs 60 and 61, Figs. 2, 3 and 7, project substantially horizontally outwardly from the end walls 52 and 53, respectively, of the cover member 24, and are so arranged thereon relative to the slots 58 that when the cover member 24 is

mounted on the base plate 22, with the legs 36a, 37a, 40a and 41a of the ears 36, 37, 38 and 41 disposed in the corresponding slots 58, as previously described, the upper edge portions of the legs 36b, 37b, 40b and 41b of the ears 36, 37, 40 and 41 are disposed below and in engagement with the lower surface of the corresponding lugs or ears 60 and 61.

It will be seen that, with this construction, when the cover member 24 is so disposed on the base plate 22, it may be raised vertically therefrom to thereby remove the cover member from the base plate 22. Also, it will be seen that when the cover member is so removed from the base plate 22, it may be replaced thereon by lowering it vertically thereover, and that when so disposed on the base plate 22, the cover member 24 is well supported against lateral movement with relation thereto, the legs 36b, 37b, 40b and 41b of the ears 36, 37, 40 and 41 being engageable with the adjacent end walls 52 and 53 of the cover member 24 to thereby restrain the cover member 24 from movement in a longitudinal direction relative to the base plate 22, and the legs 36a, 37a, 40a and 41a of the ears 36, 37, 40 and 41 being engageable with the side walls of the slots 58 within which they are disposed to thereby restrain the cover member 24 against movement transversely to the longitudinal axis thereof.

However, it will be seen that, in addition to affording novel and efficient retaining means, the ears 36, 37, 40, 41, 46 and 47, afforded on the opposite end portions of the base plate 22, and the ears 60 and 61, and the tongues 57 and 59 on the end walls 52 and 53 of the cover member 24, cooperate to afford hinges whereby the cover member 24 may be pivoted upwardly in a longitudinal direction around either end thereof. Thus, for example, it will be seen that, as shown in Figs. 2 and 3, the end 53 of the cover member 24 may be pivoted around the end 52 thereof, the upper ends of the upstanding legs 36b and 37b of the ears 36 and 37 being engageable with the lower surface of the ear 60, adjacent to the junction of the latter with the lower edge portion of the end wall 52 of the cover member 24, to thereby afford a fulcrum around which the cover member 24 may be pivoted on the ear 60. Also, it will be seen that, upon rotation of the member 24 in a counter-clockwise direction, as viewed in Figs. 2 and 3, beyond a vertical position a predetermined amount, the tongue 57 on the end wall 52 of the cover member 24 is moved into engagement with the lower surface of the upper leg 46b of the ear 46 to thereby limit rotation of the cover member 24 in this direction, and the lower surface of the ear 60 of the cover member 24 being engaged with the outer ends of the ears 36 and 37, as previously described, an effective support for holding the cover member 24 in such open position relative to the base plate 22 is thereby afforded. It will be seen that the cover member 24 may also be pivoted in a clockwise direction, as viewed in Fig. 2, around the upstanding legs 40b and 41b of the ears 40 and 41, from a closed position to an open position, the parts disposed on the right-hand portion of the cover member 24 and the base plate 22 functioning in the same manner as the corresponding parts on the left-hand portion thereof, as heretofore discussed with relation to the pivoting of the cover member 24 in a counter-clockwise direction.

Commercial gas containers such as, for example, the bottles B1 and B2 shown in the accompanying drawings, normally embody a rela-

tively narrow neck K, Fig. 2, projecting outwardly from the upper end portion thereof on which are mounted the manually operated control valves V for controlling the flow of gas from the bottle. In installations wherein commercial gas bottles of this character are commonly used to supply fuel for stoves, and the like, two or more bottles of gas are customarily connected through a common regulator R to a feed line F through which gas is fed to the consuming unit. In such installations the gas is normally used from only one bottle at a time, the control valve V on that bottle being open and the control valves on the other bottles being closed. When the gas is exhausted from the bottle being used, the control valve thereon may be closed and the control valve on the other bottle may then be opened to thereby afford a continuous supply of fuel gas while the exhausted bottle is being replaced. In such installations, the bottles affording the supply of gas are often disposed in relatively exposed places such as, for example, adjacent to the outside of the building in which the gas is being used, and, of course, it is desirable to protect the control valves and associated mechanism from the elements and from being accidentally damaged or broken by being struck by outside articles. As a result, it is customary to provide some kind of a protective covering or hood which may be disposed on the upper end portion of such bottles to protect the valves and associated mechanism. Heretofore, as previously mentioned, the common manner of supporting such a protective covering has been to afford a special stand on which the protective covering was mounted at a predetermined height as determined by the size of the gas containers being used, the stand commonly affording a base on which the bottles could be mounted. Such stands are relatively expensive to manufacture, and with my novel hood it is unnecessary to use such outside supporting devices, the hood being adapted to be supported in a novel and expeditious manner on the bottles themselves.

As is best seen in Figs. 2, 5 and 6, the base plate 22 may be mounted on the two bottles B1 and B2, simultaneously, with the necks K of the bottles disposed in, and projecting upwardly through the slots 26 and 27, respectively, and with the bosses 30 and 31 resting on the outwardly sloping shoulders of the bottles. Two nuts 65 and 66, having downwardly projecting flanges 65a and 66a, respectively, Fig. 2, are mounted on the necks of the bottles B1 and B2 in threaded engagement therewith and may be screwed down on the necks K into firm engagement with the upper surface of the plate 22 adjacent the slots 26 and 27, respectively, to thereby press the bosses 30 and 31 into firm engagement with the shoulders of the bottles. Thus it will be seen that with the base plate 22 mounted on two bottles B1 and B2 in the aforesaid manner, and the nuts 65 and 66 screwed down on the necks K into tight retaining engagement with adjacent edge portions of the base plate 22, the base plate is firmly held in proper position on the two bottles.

After the base plate is thus mounted on the bottles B1 and B2, the cover member 24 may be lowered vertically onto the base plate 22, into closed position thereon, to thereby afford an efficient practical cover member for protecting the valves V and associated mechanism, the feed line F projecting outwardly through a suitable one of the openings 48 or 49, such as, for example, the

opening 49, Figs. 5 and 6. Thereafter, when it is necessary to remove one of the bottles from the installation and replace the same with a fully charged bottle, it is unnecessary to completely remove the cover 24 from the base plate 22, it being merely necessary to pivot the cover member upwardly about the end thereof furthest removed from the bottle to be replaced, the hinge members on the cover member and the base plate 22 affording efficient means for supporting the cover member in such open position while the empty bottle is being removed and replaced with a fully charged bottle, as previously discussed. Replacement of the exhausted bottle may be readily effected by first disconnecting the connections C therefrom, unscrewing the nut 65 or 66 therefrom, and then moving the bottle outwardly through the slot 26 or 27 within which it was disposed; and, secondly, moving a new bottle into position in the slot 26 or 27, screwing the nut 66 or 67 down thereon into firm engagement with the base plate 22, and then connecting the connections C to the thus properly positioned new bottle. After the replacement of the bottle has been accomplished the cover member may again be pivoted down into closed position on the base plate 22 to afford a protective cover for the upper end portions of the bottle.

If desired, outwardly projecting lugs 70 and 71 may be afforded on the base plate 22 and the cover member 24, respectively, the lugs 70 and 71 having suitable openings 73 and 74, respectively, through which a suitable latching device such as, for example, a padlock, or the like, may be inserted to thereby retain the cover member in closed position and prevent its being opened or removed from the base plate 22 by unauthorized persons.

From the foregoing it will be seen that I have afforded a novel hood for commercial gas cylinders and the like which may be readily mounted on, and supported by, the gas cylinders on which it is to be used, and in which gas cylinders may be quickly and easily replaced in a novel and expeditious manner.

Also, it will be seen that I have afforded a novel hood wherein, although the cover member thereof is readily removable therefrom when desired, it is unnecessary to completely remove the cover member during a changeover from one bottle to another, and wherein the cover member is effectively restrained against undesired lateral displacement from the bottles on which it is being supported.

Furthermore, it will be seen that I have afforded a novel hood which is practical and efficient in operation and which may be readily and economically produced commercially.

Thus, while I have illustrated and described the preferred embodiment of my invention, it is to be understood that this is capable of variation and modification and I therefore do not wish to be limited to the precise details set forth, but desire to avail myself of such changes and alterations as fall within the purview of the following claims:

I claim:

1. A hood of the type adapted to be placed over a pair of fluid containers comprising, in combination; a base plate and a cover member, said base plate being provided with at least one vertical lug at each end thereof, an ear on said base plate adjacent the opposite ends thereof in association with each of said lugs and positioned rearwardly thereof, each of said ears

having a vertical leg projecting upwardly from said plate and a horizontal leg, said horizontal legs extending from said vertical legs in the direction of the ends of said plate and terminating short of their associated lugs to thereby define vertical passages and small lateral recesses therewith; said cover member comprising end sections projecting downwardly with respect to said base plate, the distance between said end sections being slightly less than the distance 10 between said lugs but slightly greater than the distance between the terminal points of the horizontal leg portions of said ears whereby said end sections of said cover member may be freely disposed within and withdrawn from said base plate passages; an ear on each of said end sections positioned above the terminal points thereof and thereby defining a lowermost intermediate extension on each of said end sections, said intermediate extensions being of a length approximating substantially the length of said lugs whereby said end sections may be disposed within said vertical passages to an extent determined by the seating of said cover member ears on said base plate lugs; each of the horizontal legs on said base plate ear being of a length sufficient to be engageable with the corresponding intermediate extension when the latter is rotated within its lateral recess as a result of pivoting said cover member at one end about the fulcrum established between the cover ear and base plate lug.

2. A hood of the type adapted to be used to cover the upper end portions of a pair of gas cylinders or the like comprising, in combination; a base plate having vertical lugs symmetrically disposed with respect to each other at each of the opposite ends of said base plate and a bowl-shaped cover member having end sections projecting downwardly therefrom and spaced apart a distance less than the distance between said lugs; said base plate being provided additionally with an ear adjacent either end thereof, said ears being positioned rearwardly of said lugs and each having an upper leg portion extending horizontally in the direction of said lugs but terminating short thereof, each of said ears having a second vertical leg portion from which said horizontal leg portion is extended, the body portions of said lugs and ears defining small lateral recesses and the terminal points of said lugs and said first-named leg portions defining vertical passages; said cover member having an ear projecting from each of said side sections and displaced from the bottommost terminal points thereof a distance corresponding substantially to the length of said lugs to thereby define a lowermost extension on each of said side sections; said lowermost extensions being freely vertically disposed within said passages; the first-named leg portions of said base plate ears respectively being of a length sufficient to be engageable with a corresponding one of said lowermost extensions when the latter is rotated within its lateral recess as a result of pivoting said cover member about the corresponding cover ear.

3. A hood of the type adapted to be placed over a pair of fluid containers comprising, in combination; a base plate and a bowl-shaped cover member having a top section and end sections depending therefrom; said plate being provided at each end with a pair of vertical lugs projecting therefrom, the distance between said depending end sections being slightly less than the distance between said lugs to permit said cover mem-

ber to be placed on said plate; an ear projecting upwardly adjacent either end of said plate and being disposed slightly rearwardly of and between said lugs, each of said ears being provided with a horizontal leg portion extending in the direction of said lugs but terminating short thereof, the disposition of said lugs and ears thereby defining at either end of said plate a vertical passage and a cross-sectional recess; an ear projecting from each of said end sections in the plane of said base plate and positioned slightly above the bottommost terminal points of said end sections to thereby define intermediate portions of said end sections, said intermediate portions being freely retractably disposed within said vertical passages and cross-sectional recesses to an extent determined by the seating of said cover ears on the free ends of said base plate lugs; each of said horizontal leg portions being of a length sufficient to interrupt and limit the movement of said intermediate portions when the latter are rotated within said recesses, thereby permitting said cover member to be alternatively pivoted about either end to expose a selected one of said containers.

4. A hood of the type adapted to be used to cover the upper end portions of a pair of containers comprising, in combination; a base plate and a bowl-shaped cover member, the distance between the respective depending end sections of the latter corresponding approximately to the distance between the ends of said base plate; said plate and cover member each comprising means to permit the latter to be alternately pivoted about either end of said plate to a limiting position to thereby expose one of said containers, said means comprising; lugs projecting vertically a predetermined distance from each of the respective ends of said plate, said lugs being symmetrically disposed in spaced relationship with respect to one another, ears at each end of said plate associated with and positioned rearwardly of said lugs and having horizontal leg portions extending in the direction of the plane of said base plate but terminating rearwardly of the vertical extensions of said associated lugs to thereby define with said lugs passages for free insertion of the respective end sections of said cover member therein; and ears projecting laterally from the end sections of said cover member, said cover member ears being displaced upwardly from the bottommost terminal points of said side sections a distance approximating the length of said lugs to thereby define intermediate portions of said side sections, said intermediate portions being disposable within said so-defined passages to an extent determined by the seating of said cover ears on the free ends of said base plate lugs; whereby said cover member can be pivoted on a selected one of said cover ears about an end of said base plate to an extent limited by engagement between the intermediate portion of one of said end sections and the leg portion of one of said base plate ears.

5. A hood of the type adapted to be used to cover the upper end portions of a pair of gas cylinders or the like comprising, in combination; an elongated base plate and an elongated bowl-shaped cover member complementary in outline to said plate; said base plate having respectively at each end thereof a pair of lugs projecting vertically therefrom, and an associated ear positioned between the lugs of said respective pairs of lugs, each of said ears comprising a first leg portion projecting vertically upward with respect

to said plate, and a second leg portion extending horizontally in the direction of said lugs but terminating short thereof whereby the terminal ends of said lugs and said associated ear define a vertical passage; said cover member being mounted over said base plate and comprising, a top having end sections depending therefrom, the distance between said end sections being less than the distance between said lugs but being greater than the distance between the free ends of said second-named legs, an ear projecting laterally from each of said end sections and positioned slightly above the lowermost extensions thereof a distance approximating the length of said lugs to thus define intermediate tongue-like portions on said end sections, said tongue portions being disposed within the passages defined by the terminal ends of said lugs and said associated ear to an extent determined by the seating of said cover ears on the free terminal ends of said respective pairs of base plate lugs; the length of each of said horizontal leg portions being such as to limit the movement of the corresponding tongue-like portion to a predetermined extent when the latter is

rotated as the result of pivoting the cover member about a selected end of said base plate.

ALBERT H. FINE.
